UNITED STATES PATENT OFFICE.

JAMES F. COSTELLO, OF SAN FRANCISCO, CALIFORNIA.

FORM CLAMP.

Application filed January 28, 1925. Serial No. 5,282.

To all whom it may concern:

Be it known that I, JAMES F. COSTELLO, a citizen of the Dominion of Canada, residing at the city and county of San Francisco and State of California, have invented new and useful Improvements in Form Clamps, of which the following is a specification.

This invention relates to clamps especially adapted for use in clamping together the parts of concrete forms, such as column forms and the like, the object of the invention being to generally improve and simplify the construction and operation of clamps of the character described; to render the clamps adjustable for forms of various sizes, and in general to provide clamps which may be readily and quickly applied or removed as the case may be.

One form which my invention may assume is exemplified in the following description and illustrated in the accompanying drawings, in which—

Fig. 1 is a cross-section of a concrete column showing the forms exteriorly thereof and the clamps in securing position.

Fig. 2 is a perspective view of one of the clamp arms.

Fig. 3 is a perspective view of one end of one of the clamp arms.

Referring to the drawings in detail, and particularly to Fig. 1, A indicates a concrete column which has been poured, 2, 3, 4 and 5 the forms surrounding the same, and 6, 7, 8 and 9 the clamping arms by which the forms are secured. The arms 6 and 8 are identical in construction and so are the arms 7 and 9. The perspective view shown in Fig. 2 shows the form of arm indicated at 7 and 9. It consists of a piece of strap iron 10 of suitable length, on one end of which are formed two or more hook-like members such as indicated at 11 and 12. Secured to the opposite end of the arm is a pair of triangular-shaped plates

13 and 14. These plates are secured to the opposite sides of the arm 10 and are riveted or otherwise secured. The spacing between the plates is equal to the thickness of the arm 10 and is similarly equal to the thickness of the arms 6 and 8, and the arms 6 and 8 can thus be placed between the plates 13 and 14, as will hereinafter be described.

The outer ends of the plates are provided

with a plurality of aligned slots, as shown at 15, 16, 17, 18 and 19, and these slots are provided for the reception of a wedging member such as indicated by dotted lines at 20. The arms indicated at 6 and 8, as previously stated, are also identical. One end of each arm is provided with hook-like members such as shown at 11 and 12, while the opposite end of each arm is bent to assume an angle of approximately 135°, as shown in Figs. 1 and 3, this bend being indicated at 21. Each bent portion 21 presents a shoulder and an inner face 22 which will always assume a position at right angles to the slots in the plates 13 and 14. The wedges 20, when inserted, bear against the ends of the slots and the shoulders or faces 22, and a pull will thus be exerted upon the arms when they are applied to the concrete forms, as shown in Fig. 1, which will be more than sufficient to retain them in place both before and during the pouring of the concrete.

In actual operation when the forms have been placed in position, it is only necessary to apply the clamping arms, as shown in Fig. 1; that is, the hooked ends are engaged, as indicated at 25 and 26, and the outer ends of the arms 6 and 8 are swung inwardly between the plates 13 and 14. The wedges 20 are then inserted, for instance, in the slots 17, and they will here engage the opposite ends of the slots and the shoulders 22. They may then be driven down by a hammer or other handy tool and will, during this driving action, exert a sufficient pull upon the clamping arms to bring the forms into snug engagement with relation to each other.

As the arms are constructed of strap iron or similar material, it is obvious that the strength of the same will be more than sufficient to hold the forms in position both before and during the pouring action of the concrete.

From the foregoing it can be seen that it is a simple matter to apply the arms and insert and drive the wedges into position, and it is equally as simple to release the wedges by merely tapping them on their lower pointed ends. The clamps may thus be quickly and readily applied or removed, and as several slots are provided in each of the plates 13 and 14, and the opposite ends of the arms are provided with two or more

hooks, it is obvious that a considerable range of adjustment may be had with relation to columns of different sizes.

While certain features of the present invention are more or less specifically illustrated, I wish it understood that various changes in form and proportion may be resorted to within the scope of the appended claims. I similarly wish it understood that the materials and finish of the several parts employed may be such as the experience and judgment of the manufacturer may dictate or various uses may demand.

Having thus described my invention, what I claim and desire to secure by Letters Patent is—

1. A forming clamp of the character described comprising two pairs of arms, one arm of each pair comprising an elongated flat bar having a pair of interspaced plates secured at one end and said plates having slots formed therein disposed at 45° to the longitudinal axis of the bar, the other arm of each pair also comprising an elongated flat bar, an extension on one end of each of said bars adapted to pass between the interspaced plates and having a face formed thereon disposed at right angles to the slots in the plates, means for connecting the opposite ends of the bars, and a pair of wedges insertible in the interspaced slotted plates and adapted to engage the right-angular faces of the extensions formed on the second-named bars.

2. A forming clamp of the character described comprising two pairs of arms, one arm of each pair comprising an elongated flat bar having a pair of interspaced plates secured at one end and said plates having slots formed therein disposed at 45° to the longitudinal axis of the bar, the other arm of each pair also comprising an elongated

flat bar, an extension on one end of each of said bars adapted to pass between the interspaced plates and having a face formed thereon disposed at right angles to the slots in the plates, hook-like members on the opposite ends of the bars adapted to connect the same, and a pair of wedges insertible in the interspaced slotted plates and adapted to engage the right-angular faces formed on the extensions on the second-named bars.

3. In a clamp of the character described a clamp section consisting of a pair of elongated arms, one arm consisting of a single bar, a pair of interspaced plates secured on one end of said bar, said plates having a plurality of slots formed therein disposed at an angle of 45° to the longitudinal axis of the bar, a plurality of hook members on the opposite end of the bar, said second-named arm also comprising an elongated bar, a plurality of hook members on one end, and an extension on the other end adapted to be inserted between the interspaced plates of the other arm, and said extension having a face formed thereon disposed at right angles to the slots formed in the interspaced plates.

4. In a clamp of the character described a clamp section consisting of a pair of bars adapted to be disposed at right angles to each other, one bar having a pair of interspaced plates secured at one end and said plates having slots formed therein disposed at 45° to the longitudinal axis of the bar, the other bar having an extension formed at one end adapted to pass between the slotted plates and said extension having a face formed thereon disposed at right angles to the slots, and means on the opposite ends of each bar for connecting the same to a clamp section of similar construction.

JAMES F. COSTELLO.
